(57) **CLAIM**

The ornamental design for a shoe sole, as shown and described.

DESCRIPTION

FIG. 1 is a front elevational view of a shoe sole showing the new design.

FIG. 2 is a rear elevational view thereof.

FIG. 3 is a right side elevational view thereof.

FIG. 4 is a left side elevational view thereof.

FIG. 5 is a bottom plan view thereof.

FIG. 6 is a perspective view thereof; and,

FIG. 7 is a top plan view thereof.

The broken line in FIG. 7 encloses an area that has been disclaimed and forms no part of the claimed design.

1 Claim, 5 Drawing Sheets
